UNITED STATES PATENT OFFICE.

ELMER H. TODT, OF MORRISONVILLE, ILLINOIS.

DOOR-LATCH.

No. 922,975.

Specification of Letters Patent.

Patented May 25, 1909.

Application filed December 10, 1908. Serial No. 466,794.

To all whom it may concern:

Be it known that I, ELMER H. TODT, a citizen of the United States, residing at Morrisonville, in the county of Christian and State 5 of Illinois, have invented certain new and useful Improvements in Door-Latches, of which the following is a specification.

This invention relates to latches for swinging doors, such as are desirable in connection 10 with ordinary barn doors, or the like.

The invention comprises certain specific details of construction which will be fully set forth and claimed hereinafter, and illustrated in the accompanying drawings, in which—

15 Figure 1 is a vertical face view of a door provided with the attachment, the door being held open; Fig. 2 is a similar view, the door being closed and viewed upon the opposite side from that of Fig. 1; Fig. 3 is an enlarged cross section through the door and supporting means substantially on the line 3—3 of Fig. 1, the latch mechanism being in plan, and Fig. 4 is a view on a still larger scale, the parts being in the same position as 25 indicated in Fig. 2.

Throughout the following detail description and on the several figures of the drawings similar parts are referred to by like reference characters.

30 As a convenient embodiment of the invention there is indicated in any conventional manner at 10 a swinging door hinged to a door frame 11, and adapted to be held securely either in a closed or an open position.

35 Secured to the door frame 11 is a keeper 12 having a hole or notch 12' and a flaring outer end 13. At any suitable support, such as an extension of the building or a post indicated at 14, is connected in any convenient manner

40 a second keeper 15 having a hole or notch 15' and a flaring outer end 16. The keepers 12 and 15 will be arranged at substantially the same distance from the axis of the door hinges 17.

45 The door latch is double acting, and comprises a double-L structure 18, located in a notch or recess 19 formed in the outer edge of the door and pivoted on a stationary support, shown in the form of a staple 20 secured in 50 the door at the bottom of said recess 19, so as to swing in a plane transverse to the plane of

the door. The nose 18' of the catch extends outwardly in a direction parallel with the general plane of the door and is adapted to coöperate with either of the flared portions 55 of the respective latches and to enter the hole adjacent thereto for holding the door in the position to which it is being moved at that time. I prefer to employ in connection with the latch a spring to insure the engagement 60 of the nose 18' with the keepers. Such spring is shown as being of the coiled species at 21 and is mounted within and projects through a hole 22 through the door adjacent to the recess 19. One end of the spring is anchored to 65 a washer 23 on one side of the door, and the other end of the spring is secured to the latch in a hole 24 from the opposite side of the door. The normal tendency of the spring, therefore, is to maintain the nose of the latch 70 in engagement with one or the other of the keepers, or in such a position with respect to the door as to insure its engagement with the keepers when the door is swung to either extreme position. The nose 18' may be withdrawn from the keepers by any suitable 75 means. I have shown, however, for this purpose a pull-piece 25 connected to one end of the latch for manipulation thereof on one side of the door, and a pull-piece 26 connect- 80 ed to the other end of the latch adjacent to the nose 18' for manipulation of the latch on the opposite side of the door. The pull-pieces 25 and 26, being pivoted to the latch, may occupy any convenient angle with respect thereto.

Having thus described the invention, what is claimed as new is:

1. The combination with a door frame and a door pivoted thereto, of a pair of keepers, a latch of double-L form pivoted transversely of the door and extending upon opposite sides thereof, the latch having a nose for co-operation with either of said keepers, means to cause the latch to swing on its pivot and 90 maintain it in engagement with either keeper, and means connected to the opposite ends of the latch whereby the same may be operated from either side of the door.

2. The combination with a door frame and a door pivoted therein, of a pair of keepers, a door latch of double-L form located in a re-

cess in the edge of the door and pivoted therein to swing in a plane transverse to the plane of the door, said latch having a nose for coöperation with either of said keepers, a spring anchored at one end on one side of the door and secured to the latch at the other end to maintain the latch in position to engage either keeper, and a pull piece connected to each end of the latch whereby the same may

be operated from either side of the door, substantially as set forth.

In testimony whereof I affix my signature in presence of two witnesses.

ELMER H. TODT.
